Inventor

UNITED STATES PATENT OFFICE.

J. JOSEPH HENRY, OF BALTIMORE, MARYLAND.

SOLDERING-TOOL.

SPECIFICATION forming part of Letters Patent No. 371,841, dated October 18, 1887.

Application filed June 18, 1887. Serial No. 241,721. (No model.)

To all whom it may concern:

Be it known that I, J. JOSEPH HENRY, of Baltimore city, in the State of Maryland, have invented certain new and useful Improvements 5 in Soldering-Machines for Capping Preserving-Cans; and I do hereby declare that the following is a full, clear, and exact description thereof, reference being had to the accompanying drawings.

10 My invention consists in the construction and arrangement of certain parts of a soldering-tool for closing or capping preserving cans.

The several parts of this device are herein-
15 after more particularly set forth, and illus-
trated by the accompanying drawings, forming
part of this specification.

Figure 1 is a side elevation of the complete
tool. Fig. 2 is an axial section of the handle.
Figs. 3, 4, 5, and 6 are detail views.

20 In the drawings, Fig. 1, A represents a cen-
tering-rod, pointed at its lower end and having
a wooden handle, J, on the top end.

B represents the wooden body of the tool.

C represents a metallic tube passing upward
25 through the slot in the slide E and continuing
upward through the center of the wooden
body, fitting loose enough to admit of an easy
adjustment of the slide E. This tube is threaded
at its upper end, as seen in Fig. 5, to connect
30 it with the clamping-nut I, as seen in Fig. 2.
The tube C is threaded at its lower end, upon
which is screwed and riveted the head D, which

head should be large enough to embrace both
sides of the slide E when drawn up against it by
means of the clamping-nut I. The slide is 35
held firmly against the ferrule on the lower
end of the wooden body.

E represents the slotted slide. It is pierced
at its solid end with a round hole to receive
the shank F of the soldering-iron H. 40

G is a thumb-screw, which adjustably holds
the shank F of the iron H. K is a ferrule on
the lower end of the handle B, against which
the slide E is clamped.

I am aware that prior to my invention soldering-tools have been made having some parts
of them similar to mine. I therefore do not
claim such a combination, broadly; but I in-
tend by this improvement to place the clamp-
ing-nut in such a position at the top of the 50
wooden body as to be free from the oxidizing
and destructive influence of the flame from the
heating-furnace.

What I claim as my invention, and desire to
secure by Letters Patent, is— 55

The tube C, fitting loosely in the center of
the wooden body B, and threaded at its upper
end, and having a head upon its lower end, in
combination with the clamping-nut I and slide
E, substantially as set forth.

J. JOSEPH HENRY.
